Charles R. Scarle,

UNITED STATES PATENT OFFICE.

ABRAHAM FRIEDMAN, OF NEW YORK, N. Y., AND ARTHUR F. KNOWLES, OF UPPER MONTCLAIR, NEW JERSEY.

AIR DIFFUSER.

Application filed May 26, 1921. Serial No. 472,645.

To all whom it may concern:

Be it known that we, ABRAHAM FRIEDMAN, a citizen of the United States, residing in the city of New York, in the borough and county of Queens and State of New York, and ARTHUR F. KNOWLES, a citizen of the United States, residing at Upper Montclair, in the county of Essex and State of New Jersey, have invented a certain new and useful improvement in Air Diffusers, of which the following is a specification.

The invention relates to devices for delivering air from floor ducts in ventilating systems, and the object of the invention is to provide a simple, economically constructed diffuser adapted to be conveniently located beneath the chair and to receive air from a duct and deliver it directly to the auditorium with a minimum of friction, and to be shaped that it is not likely to cause accidents by being used as a foot-rest by the occupant of the next chair in the rear.

Another important object is to provide means for preventing the entrance of dust and waste matter into the delivery openings of the diffuser, and a further object is to provide easily operated adjusting means for varying the volume of air delivered through such openings.

The invention consists in certain novel features and details of construction and arrangement by which the above objects are attained, to be hereinafter described and claimed.

The accompanying drawings form a part of this specification and show the invention as it has been carried out in practice.

Figure 1 is a perspective view showing a portion of a row of theatre chairs, with an improved diffuser in place.

Figure 2 is a side elevation of one of the diffusers alone, on a larger scale, and partly in vertical section.

Figure 3 is an end view of the same.

Figure 4 is a plan view corresponding to Figure 2 and partly in horizontal section.

Figure 5 is a transverse section taken on the line V—V in Figure 2.

Figure 6 is a vertical section corresponding to a portion of Figure 2, showing certain details on a still larger scale.

Referring to the drawings, 1 is the floor having an opening 2 leading from a duct or air conduit, not shown, forming part of the air supply system beneath the floor.

The diffusers are located at intervals beneath the seats 3 and each comprises a box-like casing or shell of rectangular form in plan view, preferably a thin casting, open at the bottom to match the floor opening 60 from the duct, and open at the ends to permit the egress of air. The sides 4 of the casing are higher at the ends, and the upper faces 5 are correspondingly inclined, as shown, to a flattened V-form, so that the 65 casing is flared oppositely and the air led with little friction from the duct to the open delivery ends, while providing a shape which is economical of metal and, because of its sharp exterior angles, not likely to 70 be used as a foot-rest.

The casing is secured to the floor by screws extending through holes in the flanges 13 on the sides 4.

At each open end on each side on the interior are vertical grooves 7 formed by the spaces between the vertical ribs 6 extending from the top nearly to the lower edges of the sides 4 and forming ways in which a screen 8 of wire mesh is slidably 80 mounted covering the end and serving to exclude paper and other refuse articles with which the auditorium floor is likely to be littered, and the lower margin of the screen is held and stiffened between a strip 85 of sheet metal 9 on the inner face and the upright portion 10 of an angular strip on the outer face, the horizontal member or flange 11 of which extends beneath the ribs 6 and lies upon the floor, as clearly shown 90 in Figure 6. The strips 9 and 10 are joined to the margin of the screen by rivets 12 extending therethrough.

Beside stiffening the margin of the screen, the upright portion 10 and horizontal portion 11 of the outer strip serve to prevent the ingress of dust and the like in the operation of cleaning the auditorium floor.

The shape of the diffusers permits the casing to be low without interfering with 100 the easy unobstructed delivery of air, a factor of importance in installations in auditoriums equipped with low-slung seats, and by directing the currents in opposite directions longitudinally of the row of seats, the 105 fresh air is introduced without discomfort to the chair-occupants.

By reason of the large admission and delivery areas, due to the shape of the improved diffuser, a smaller number may be 110

employed to supply the required volume of air, thus effecting a saving in air-duct construction.

In the complete form of the invention, as illustrated in the drawings, two independent dampers 14 are provided within the casing, one for each end, by which the flow of air may be controlled. Each damper comprises a plate of sheet metal mounted upon a transverse shaft 15 near the centre of the casing, having a handle 16 on the exterior by which the plate may be raised or lowered to expose more or less of the open end, and the handle is arranged to engage in notches 17 on a segment 18 to hold the damper in the adjusted position.

We claim:-

1. The diffuser described, comprising a casing open at the ends and bottom and closed at the opposite sides and having its sides and top upwardly and oppositely inclined from the centre, adapted to receive air through such bottom and deliver it oppositely simultaneously through such flared ends.

2. The diffuser described, comprising a casing open at the ends and bottom and closed at opposite sides and having its sides and top upwardly and oppositely inclined from the centre, adapted to receive air through such bottom and deliver it oppositely through such flared ends, and open-work screens covering the openings at such ends, the opening in the bottom being continuous from end to end.

3. The diffuser described, comprising a casing open at the ends and bottom and

having its sides and top upwardly and oppositely inclined from the centre, adapted to receive air through such bottom and deliver it oppositely through such flared ends, openwork screens covering the openings at such ends, and an angular transverse strip on the lower margin of each of said screens, having a vertical portion lying against said screen, and a portion extending horizontally from said screen and adapted to lie upon the floor.

4. The diffuser described, comprising a casing open at the ends and bottom and having its sides and top upwardly and oppositely inclined from the centre, adapted to receive air through such bottom and deliver it oppositely through such flared ends, and a horizontally disposed damper in each of said ends arranged to swing vertically and control the flow through such ends.

5. The diffuser described, comprising a casing open at the ends and bottom and having its sides and top upwardly and oppositely inclined from the centre, adapted to receive air through such bottom and deliver it oppositely through such ends, a horizontally disposed damper in each of said ends arranged to swing vertically and control the flow through such ends, and means on the exterior of said casing for moving said dampers independently and holding them in the adjusted position.

In testimony that we claim the invention above set forth we affix our signatures.

ABRAHAM FRIEDMAN.
ARTHUR F. KNOWLES.
